UNITED STATES PATENT OFFICE.

CHARLES H. KNAPP, OF PATERSON, NEW JERSEY.

WARPING AND BEAMING MACHINE.

SPECIFICATION forming part of Letters Patent No. 630,611, dated August 8, 1899.

Application filed March 2, 1899. Serial No. 707,458. (No model.)

To all whom it may concern:

Be it known that I, CHARLES H. KNAPP, a citizen of the United States, residing in Paterson, in the county of Passaic and State of New Jersey, have invented certain new and useful Improvements in Warping and Beaming Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention constitutes an improvement in beaming attachments for warping-mills.

The object of the invention is to provide a beaming attachment which shall be strong and durable in construction, effective in operation, and whose parts are—such as should be, for the reason of necessity or convenience—readily adjustable and removable.

20 The invention consists in the improved beaming attachment, in the combination thereof with a warping-mill, and in the combination and arrangement of the various parts of said beaming attachment, substantially as will be hereinafter pointed out, and finally embodied in the clauses of the claim.

25 The invention is fully illustrated in the accompanying drawings, wherein corresponding letters of reference designate like parts, and wherein—

Figure 1 is a view in side elevation of a portion of a warping-mill with my improved beaming attachment mounted thereon. Fig. 3 is a top plan view of said beaming attachment. Fig. 3 is a vertical sectional view taken on the line $x-x$ of Fig. 2 at one end of 30 said figure. Fig. 4 is a vertical transverse sectional view on the line $y-y$ of Fig. 3. Figs. 5, 6, and 7 are views of certain details of my invention, Fig. 6 being a transverse sectional view on the line $z-z$ of Fig. 4; and Fig. 8 is a 35 view in elevation of a portion of the frame of said beaming attachment.

In said drawings, a designates the frame of the warping-mill, having the usual reel b journaled thereon and carrying my improved 40 attachment at or near one of its ends and supported upon the upper side rails a' of said frame. The frame of said beaming attach-

ment consists of two end plates c c' , connected by four bars d , the ends of said bars being bolted to said plates. The end plate c 55 may be of any suitable shape, and it is provided with a supporting-flange c^2 , whereby said end plate is sustained upon one of the side rails a' of the frame of the warping-mill, said flange being adapted to rest upon the top of the rail. The end plate c' also has a flange c^2 , whereby it is sustained upon one of the rails a' opposite to the end plate c . At d' this end plate is considerably bent out of the line of its general plane, so as to form 60 a recess d^2 , and in the bent-out portion thus formed there is an integral bearing d^3 , adapted to support a certain shaft hereinafter referred to. A side elevation of this end plate is shown in Fig. 8.

70 e designates a stud which projects outwardly from the end plate c' and to which is bolted a gear-casing e' , which it supports, said gear-casing being also sustained by an overhanging projection e^2 , extending from the top of the end plate c' and which is bolted to said gear-casing.

f indicates a bracket which projects outwardly and downwardly from the end plate c' , being either integrally formed therewith or preferably bolted thereto. Said bracket f has two downwardly-extending arms f^1 f^2 and a standard f^3 , having a bearing f^4 at its upper end and extending downwardly approximately as far as the arms f^1 f^2 , the arms and the standard being preferably integral portions of the bracket. The bearings d^3 and f^4 provide journals for a shaft g , which carries fast and loose pulleys g^1 and g^2 and also other pulleys g^3 g^4 , the latter pair of pulleys being 80 adapted to transmit motion from the shaft g to the warping-mill, so as to rotate the reel thereof and relieve the warp-threads of any undue strain. In the drawings the pulleys g^3 g^4 are shown as being connected by a belt 85 with the usual drive-wheel g^5 for the reel of the warping-mill.

90 h designates a belt-shifter which is fulcrumed at h' in the bracket and which is controlled by a spiral spring h^2 , connected to the lower end of the standard f^3 and to a lug h^3 on the lower end of said belt-shifter, said lower end of the belt-shifter being movable between the arms f^1 f^2 , which are provided with set-

screws f^5 for regulating the movement or throw of said belt-shifter.

i^i are horizontal shafts which are journaled at their ends in the end plates c^i in a plane slightly beneath that of the bars d , each shaft being disposed between two of said bars and each having a key i^2 .

j^j are gear-wheels carried on the ends of shafts i^i , respectively, which are the nearer to the driving-pulleys $g^1 g^2$, and j^2 is an intermediate pinion which is journaled upon the stud e and which transfers the movement from the one to the other of said gears.

The shaft g has a key j^3 , and it carries a pinion j^4 , provided with a feather engaging said key and formed integrally with a sleeve j^5 , which projects from the side thereof away from the pulleys g^3 and g^4 , and also has a pair of collars or flanges j^6 . The pinion j^4 is adapted to be moved laterally or longitudinally of the shaft g , so as to throw it in and out of engagement with the gear j , to which it transfers motion from the shaft g , and for this purpose a rock-shaft k is provided, said rock-shaft being journaled in the bent-out portion d' of the plate c' and also in a web k' , which connects said end plate and its flange c^2 , and it (the rock-shaft) has at one end a handle k^2 and at its other end a fork k^3 , provided with oppositely-disposed and inwardly-projecting lugs k^4 , which extend toward the sleeve j^5 and between the flanges thereof. It will be seen that by manipulating the rock-shaft k the pinion j^4 may be moved laterally so as to effect the making and breaking of its connection with the gear j .

l is a pawl which is fulcrumed upon a pin l' , projecting from an upwardly-extending lug l^2 , formed on the top of the end plate c' , said pawl being adapted to engage the teeth of and prevent backward rotation of the gear j and extending through an opening l^3 in the top of the gear-casing e for that purpose.

m designates a series of brackets which are adapted to support and form journals for the corresponding ends of the shafts m' of the several beams m^2 . Each of said brackets consists of a substantially three-armed frame, one arm of which has a bearing m^3 for the end of the shaft m' of the beam and the other arms of which are provided with collars m^5 , which are adapted to receive the rods d , one of the collars being split and formed with a pair of lugs which take a set-screw m^4 . By means of this split collar and set-screw the bracket is rendered adjustable longitudinally of the rods d .

n designates combined gear-casings and brackets, which are adapted to support the other ends of the shafts m' of the beams m^2 . The bracket portion n' of each combined bracket and gear-casing is substantially the same in outline and construction as the bracket m already described. The gear-casing n^2 is integrally formed therewith and is open upon the side opposite therefrom. It should be remarked that the upper end of the arm of the bracket n , in which the end

of the shaft m' is journaled, is provided with a wide bearing n^3 .

o designates a short shaft which is journaled in the bearing n^3 and which carries at the end thereof adjacent the beam m^2 a face-plate o' , having a pin o^2 , which is adapted to engage a corresponding orifice in the adjoining end disk o^3 of the beam m^2 and the other end of which carries a gear o^4 . The gear o^4 is in mesh with a pinion o^5 , having a feather-way o^6 , which receives the key i^2 of the shaft i , said gear o^4 and pinion o^5 being in engagement with each other and inclosed in the gear-casing. A suitable plate o^7 is bolted to the gear-casing, said plate bridging the pinion and gear at their junction and serving to hold them in place. A collar o^8 , provided with a set-screw o^9 , is formed upon the gear, so as to hold the latter in place, which is removable from said shaft.

It will be obvious that although I have provided but two pinions, whereby power is transmitted from the shaft i or i' to the shaft o of each beam, a train of pinions, in whatever arrangement, may be employed, if desired or necessary, and hence I do not wish to limit myself to the two pinions which I have particularly described.

It should be remarked that the gear-casing is provided in its lower portion with an opening p , which is contracted at its lower end, being so shaped that its lower portion approximately fits into a groove p' , formed between the pinion o^5 and a flange p^2 , surrounding a collar p^3 , projecting from said pinion, while its upper portion is large enough to permit the removal of the flanged collar on the pinion o^5 from said opening and its disengagement from the casing. By the construction just described the pinion o^5 is maintained in alignment and engagement with the pinion o^4 .

The staggered arrangement of the several beams which are carried upon the two pairs of bars d is effected according to a well-known construction, so that the least possible space may exist between the warps taken off by any two beams.

In operation, motion being transmitted from a driving-belt for the machine to the fast pulley of the pulleys $g^1 g^2$, the shaft g will be rotated, and the rock-shaft having been first manipulated so as to move the pinion j^4 into mesh with the gear j^5 rotary motion will be imparted from said pinion j^4 to the system of gearing comprising the pair of gears j^j and the intermediate pinion j^2 . The gears j^j will effect the rotation of the shafts i^i , and consequently also the rotation of the pinions o^5 , which will in turn impart movement to the pinions o^4 , whereby the beams are revolved, through the shafts o and the face-plate o' , which engage the disk o^3 of said beams. Rotary motion is imparted from the pulleys $g^3 g^4$, carried upon the shaft g , to the drive-wheel g^6 for the reel b . The operative connection thus provided for between the reel b and the shaft g may be constantly maintained during

the operation of the machine, or it may be only effected when the machine is started, so as to overcome the inertia of the reel b and a consequent strain upon the warp. In the latter case any well-known means for making and breaking this connection at present in use may be employed. I have shown in the drawings a lever q , which constitutes one of a pair which take against the under side of the ends 10 of other levers q' , which provide bearings for the drive-wheel g^2 . Both these levers are fulcrumed in the frame a of the warping-mill, the first-named pair being adapted to be so operated in the well-known manner as to raise 15 the other pair, and consequently the drive-wheel, and effect an engagement between the pulley q^2 , forming a portion of said drive-wheel, and the periphery of a flange q^3 of said reel. The part of the machine just referred 20 to is old and well known in the art and needs no further or more definite description, it constituting no portion of my invention.

Having thus fully described my invention, what I claim as new, and desire to secure by 25 Letters Patent, is—

1. A beaming attachment for warping-mills consisting of a frame, end plates included in said frame, one of said end plates having a bent-out portion a pair of beam-operating 30 shafts journaled in said end plates, gearing operatively connecting said shafts, a drive-shaft having suitable rotating means, a pinion keyed onto said shaft and adapted to operatively engage said gearing, and a rock-shaft 35 operatively connected to said pinion, having bearings in the bent-out portion, and adapted to reciprocate said pinion into or out of operative engagement with said gearing, substantially as described.

2. In a beaming attachment for warping-mills, the combination, with a frame comprising end plates and pairs of bars connecting them, one of said end plates having an overhanging projection, of a stud projecting 40 from said end plate, a pair of beam-carrying shafts journaled in said end plates, a gear carried by each beam-carrying shaft, an intermediate pinion operatively engaging said gears and journaled on said stud, a gear-casing 45 secured to said overhanging projection and the stud, a bracket projecting from said last-mentioned end plate, a drive-shaft journaled in said bracket and the last-mentioned end plate and having suitable rotating means, a pinion keyed onto said drive-shaft and 50 adapted to operatively engage one of the gears, and a rock-shaft operatively connected to said pinion and adapted to reciprocate the same into or out of operative engagement 55 with said beam-carrying shafts, substantially as described.

3. In a beaming attachment comprising a frame having a pair of connecting-bars, a beam-carrying bracket consisting of a three- 60 armed frame, one of the arms of which affords a bearing for the beam and the other arms of which are provided with collars

adapted to receive the bars, and one of said collars being split and provided with a set-screw, and a gear-casing integrally formed 70 with said frame, substantially as described.

4. In a beaming attachment for warping-mills, the combination, with a frame having a pair of connecting-bars, of brackets adjustably mounted on said connecting-bars, a beam revolvably mounted in each pair of brackets, a revolvably shaft journaled in said frame and having suitable operating means, a gear journaled in one of the brackets of each pair of brackets and operatively connected to the 80 corresponding beam, and a pinion meshing with said gear and mounted on said shaft, substantially as described.

5. In a beaming attachment for warping-mills, the combination, with a frame having 85 a pair of connecting-bars, of brackets adjustably mounted on said connecting-bars, a beam revolvably mounted in each pair of brackets, a gear-casing integrally formed with one of the brackets in each pair of brackets, a 90 revolvably shaft journaled in said frame and having suitable operating means, a gear inclosed in said gear-casing, journaled in the corresponding bracket and operatively connected to the corresponding beam, a pinion 95 keyed onto said shaft, also inclosed in said gear-casing, and meshing with said gear, and means for maintaining said pinions in engagement with said gear, substantially as described.

6. In a beaming attachment for warping-mills, the combination, with a frame having a pair of connecting-bars, of brackets adjustably mounted on said connecting-bars, a beam revolvably mounted in each pair of brackets, 105 a gear-casing integrally formed with one of the brackets in each pair of brackets, a revolvably shaft journaled in said frame and having suitable operating means, a gear inclosed in said gear-casing, journaled in the corresponding bracket and operatively connected to the corresponding beam, a pinion keyed onto said shaft, also inclosed in said gear-casing and meshing with said gear, and a plate 110 spanning said pinion and the gear at their junction and secured to said gear-casing, substantially as described.

7. In a beaming attachment for warping-mills, the combination, with a frame having a pair of connecting-bars, of brackets adjustably mounted on said connecting-bars, a beam revolvably mounted in each pair of brackets, a gear-casing integrally formed with one of the brackets in each pair of brackets, a revolvably shaft journaled in said frame and having suitable operating means, a gear inclosed in said gear-casing, journaled in the corresponding bracket and operatively connected to the corresponding beam, and a pinion keyed onto said shaft, meshing with said gear, and 125 inclosed in said gear-casing, said pinion being provided with a flanged collar operatively and disconnectingly engaging said gear-casing, substantially as described.

8. In a beaming attachment comprising a frame having a pair of connecting-bars, a beam-carrying bracket consisting of a three-armed frame, said frame being sustained on the connecting-bars, a gear-casing integrally formed with said last-named frame and provided with an opening having a contracted lower end, a gear journaled in said three-armed frame and inclosed in said gear-casing, and a suitably-journaled pinion also inclosed in said gear-casing and meshing with said gear, said pinion having a flanged collar received by the contracted end of the opening in said gear-casing, substantially as described.
- 15 9. In a beaming attachment comprising a frame having a pair of connecting-bars, a beam-carrying bracket consisting of a three-armed frame, said frame being sustained on the connecting-bars, a gear-casing integrally

formed with said last-named frame and provided with an opening having a contracted lower end, a gear journaled in said three-armed frame and inclosed in said gear-casing, a suitably-journaled pinion also inclosed in said gear-casing and meshing with said gear, 25 said pinion having a flanged collar received by the contracted end of the opening in said gear-casing, and a plate spanning said pinion and the gear at their junction and secured to the gear-casing, substantially as described.

In testimony that I claim the foregoing I have hereunto set my hand this 20th day of February, 1899.

CHAS. H. KNAPP.
